UNITED STATES PATENT OFFICE.

JEWETT FOWLER NEILEY, OF ENDICOTT, NEW YORK.

STAMPING ATTACHMENT FOR HIDE SPLITTERS.

1,416,967.

Specification of Letters Patent. Patented May 23, 1922.

Application filed July 27, 1921. Serial No. 487,997.

To all whom it may concern:

Be it known that I, JEWETT F. NEILEY, a citizen of the United States, residing at Endicott, in the county of Broome and State 5 of New York, have invented certain new and useful Improvements in Stamping Attachments for Hide Splitters; and I hereby declare that the following is a full, clear, and exact description thereof, reference being 10 had to the accompanying drawings, which form part of this specification.

This invention is a novel mechanism for stamping green hides, before placing same in the tanning liquors, in order to identify 15 the particular kind of hide by the stamp; and also includes novel means for making small incisions in the split halves of the hide to enable the two halves to be readily tied together for subsequent treatment.

20 The invention is especially adapted for connection with the splitting "horses" on which the hides are usually split preparatory to tanning; but may be used separately thereupon if desired.

25 In the common method of stamping hides, after the green hide is thrown over the "horse", and before the hide is split, a die attached to the head of a hammer-like instrument is forcibly brought down upon the hide by successive strokes to impress the outline of the die in the surface of each half of the hide, the stamp being usually made at the head end or butt end of the hide. After the stamping the operator splits the 30 hide with a knife and then customarily makes a small incision in each half of the hide with a short bladed knife, near the split therein to enable the halves of the hide to be tied together by a cord inserted through 35 such incisions whereby the halves of the hide are kept together during the tanning thereof.

40 My present invention is particularly designed for use in connection with such hide splitting "horses" and enables both halves of the hide to be simultaneously stamped, and incisions to be simultaneously made in each half of the hide, to enable the halves to be tied together.

45 50 55 In the accompanying drawings I have illustrated one practical embodiment of the invention as attached to an ordinary hide-splitting "horse" and will explain the same with reference to said drawings; and summarize in the claims the essentials of the

invention and the novel features of construction and novel combination of parts for which protection is desired,

In said drawings:

Figure 1 is a side view of part of a hide-splitting "horse" showing my novel stamping and incising devices applied thereto.

Figure 2 is a detail top view of Figure 1.

Figure 3 is an end view of Figure 1.

Figure 4 is an enlarged detail sectional view looking downward on line 4-4, Figure 1.

Figure 5 is an enlarged vertical sectional view on the line 5-5, Figure 1.

A, A, designate the parallel top bars of a 70 hide-splitting "horse" arranged horizontally and slightly separated and supported by legs B which may be connected at the bottom by a tie-rod and may be fastened to the bars A, A and to each other by bolts D (see 75 Figures 1, 2 and 3). The particular construction of the "horse" is not a feature of the present invention; it may be of any suitable construction.

Adjacent one end of each bar A is a 80 stamping member 1, which is preferably attached to the upper end of a vertically disposed shaft 1^e guided in a sleeve 1^f attached to the adjacent bar A. The stamp member 1 is provided on its under side with a socket 85 for the reception of a removable stamp or die S which can be secured thereto by a bolt 1^a; the face of the die S projects below the lower side of the member 1, but is held by said member above the top of the 90 bar A, when shaft 1 is in normal position as in Figures 1 and 2. Preferably a lead block 1^b is inserted in a recess in the upper side of each bar A below and adjacent the related die S and serves as a platen for such 95 die. The member 1 may be formed on or fastened to the upper end of shaft 1^e in any suitable manner. As shown it is formed separately and has an opening in one end fitted to the shaft and secured thereto in 100 any suitable manner, preferably so that said member can be adjusted both vertically and also rotatably on the shaft 1^e, so as to insure proper positioning of the cutter S relative to the block 1^b.

105 Each shaft 1^e, is preferably reduced in diameter below the sleeve 1^f, as at 1^g; and to the reduced portions 1^g are attached members or castings 2 (see Figure 4) having arms 2^a, which are connected by a stout con- 110

tractile helical spring 2^e. The castings 2 have other arms 2^b, which project approximately at right angles to arms 2^a, and each arm 2^b is connected by a link 2^f to one arm 5 of a bell crank lever 3, the other arm of which lever preferably carries a roller 3^a and engages the treadle lever hereinafter referred to.

Preferably each link 2^f is pivotally connected to the head of a pin 2^e engaging a vertical opening in the related arm 2^b; and the other end of the link 2^f is pivotally connected to a pin 3^b in the end of the upper arm of the bell crank lever 3, these connections permitting relative oscillating and rocking movements of the arms and lever.

The lower end 1^g of each shaft 1^e extends through an opening in a vertically movable bar 4, and is suitably connected therewith 20 so as to be moved thereby. Preferably a ball thrust bearing 4^a is interposed between the upper side of the bar 4 and the casting 2; and a similar ball thrust bearing 4^b is interposed between the underside of the bar 25 4 and a collar 1^c on the lower end of part 1^g of the shaft below the bar, said collar being retained on the shaft by a nut 1^h, or other suitable means.

The bar 4 may be raised or lowered, to 30 raise or lower the shafts 1^e and stamp members 1, by any suitable means. As shown an eye bolt 5 is attached centrally to the bar 4, and to this eye bolt is pivotally connected the upper ends of links 5^a which depend on 35 opposite sides of an angular treadle lever 6 and are pivotally connected to the knee of said lever as at 5^b. The end of the short arm of this treadle lever is pivoted at 6^a to suitable supporting bars 9 attached to the horse 40 as shown. The long arm 6^b of the treadle lever extends upwardly and outwardly and has a flat upper edge which is engaged by the roller 3^a of the lever 3 (see Figure 1).

The treadle lever 6, bar 4, shafts 1^e, and 45 stamp members 1, are normally held in the position indicated in Figure 1, by means of suitable springs. Preferably a rod 7 is pivotally connected to the pin 5^b intermediate the links 5^a, said rod 7 may be threaded and 50 adjustably secured to the pin by nuts 7^a, as indicated in dotted lines in Figure 1. On the outer end of rod 7 is hung a plate 7^b to which are connected stout contractile springs 8, the outer ends of which are connected to 55 a plate 8^a attached to a convenient part of the frame or base as shown. Any other suitable arrangement of springs may be used to hold the stamp carrying members 1 and the treadle normally in elevated position, as in Figure 1.

In the construction shown when the lever 6 is depressed shafts 1^e and stamps 1 are depressed so as to bring the stamps into contact with the hides overlying the blocks 1^b; 65 the springs 8 being more powerful than the

spring 2^e; when the lever 6 is released its ends 6^b raises and the roller 3^a engaging 6^b rocks lever 3 into the position shown in full lines in Figure 1, and through the connections cause the shafts 1^b to turn as they 70 rise, and cause the stamp members 1 to swing laterally outwardly away from each other to the position (shown in full lines in Figure 2). The stamps are thus moved from positions directly above the blocks 1^b, and 75 sufficient space is left between the members 1, when the parts are in raised position to enable the workman to readily adjust the hide on the horse in the usual manner in position for stamping and cutting. When the treadle is depressed and shafts 1^e and members 1 lowered, the spring 2^e causes the shaft 1^e to turn as they descend and the members 1 swing inwardly toward each other to the position shown in dotted lines 80 in Figure 2 and bring the stamps directly over the blocks 1^b and impress the hide closely adjacent the slot *a* between the bars A.A.

The inturning movement of the stamping members enables the stamps to be applied very close to the edges of the halves of the hide. A knife can then be inserted in slot *a*, between bars A.A, and the hide split into two parts as it rests on the horse. The hide 95 can be split while the stamps are held engaged therewith and this assists in keeping the split or cut straight, so that the cut edges of the halves when tanned are straight instead of irregular.

Any other suitable means may be employed to cause the shafts or stamping members to turn toward each other or the center line of the horse as they are depressed, and to separate as they are elevated.

Preferably a cutter or knife C is attached to the under side of each stamp block 1 between the stamp S and the shaft; and so positioned that when the dies are depressed to stamp the hides incisions about one and one-half inches in length are made at the same time by the cutters C in each half of the hide adjacent to the stamp. These incisions enable the two halves of the hide to be readily tied together and thus treated alike during the tanning process as is customary. In the process commonly used the tanner cuts slits in the hide with a short bladed knife after splitting it for tying the halves together and this has resulted in a lack of 115 uniformity in the sizes of the slits, and increases the time and amount of work involved in preparing the hides, as compared with the amount of work required when my invention is used.

By the addition of the cutter C the number of operations necessary to prepare the hides for the vats is reduced, because these incisions are an essential step in the process of preparing the hides for tanning, and by 130

my invention they are automatically made in each hide before it is placed in the vat.

Obviously changes may be made in the particular construction of the parts while retaining the essential and novel features of invention. I therefore do not consider the invention restricted to the specific embodiment thereof shown in the drawing.

Operation.

10 A green hide is thrown over the horse and the head or butt portion of the hide is inserted under the members 1 and over the blocks 1^b. Then the operator depresses the 15 treadle 6 with his foot thereby bringing the stamps forcibly down upon the hide and impressing the stamps thereon. At the same time the cutters C make small incisions or slits in the halves of the hides to enable 20 them to be tied together. After the impressions and incisions have been made, and preferably while the hide is clamped by the stamps, the hide may be slit from head to tail by the operator drawing a sharp knife 25 lengthwise between the two top bars of the horse.

Some of the advantages of my invention are: the stamps are made exactly in the same place on each half of each hide; they are 30 thoroughly legible; the work is uniform; the stamping is greatly facilitated; as the operator by simply depressing the treadle performs operations that heretofore ordinarily required four operations by hand, to wit, 35 picking up a hammer, with die inserted in the face, striking each side once with the hammer and then laying down the hammer. Additional advantages are the simultaneous 40 making of the slits or incisions in the halves of the hide, at the same time the stamps are made with no extra work on the part of the operator; the mechanism is simple and no special skill is required by a workman to operate it; and the parts are automatically returned to original position by the springs 45 when the treadle is released.

What I claim is:—

1. In a machine of the character specified 50 a movable member; means to depress said member, spring means for normally holding the member in raised position; and means for turning the member in one direction as it rises and in the opposite direction as it lowers substantially as described.

55 2. In a machine of the character specified a pair of movable members; means adapted to depress the same; spring means for normally holding the same in raised position; and means for turning the members toward 60 each other as they are depressed; and for turning them away from each other as they rise.

65 3. In combination a member having a depending shaft; a pivotally supported treadle; connections between the treadle and

the shaft for operating the latter, springs for returning the shaft to normal position; means for turning the said member in one direction as it moves to operative position and for turning the member in the opposite direction as it is moved away from operative position.

4. In combination, a member, a shaft carrying said member; a treadle; a connection between the treadle and the shaft for raising and lowering the latter; springs for returning the shaft to normal position; and means for turning the shaft and member in one direction as the shaft is lowered; and means for turning the shaft and member in the opposite direction as the shaft is raised, substantially as described.

5. An attachment for a hide splitting horse comprising a movable member attached to the horse; means to depress said member, 85 spring means for normally holding the member in raised position; and means for turning the member as it rises and lowers.

6. A stamping attachment for a hide splitting horse comprising a pair of movable 90 members attached to the horse; a treadle and connections adapted to depress the members; and spring means for normally holding the treadle and members in raised position; with means for turning the members toward 95 each other as they move to operative position and for turning them away from each other as they move away from operative position.

7. In combination a stamping member, a 100 shaft carrying said member; a pivotally supported treadle; an adjustable connection between the treadle and the shaft for operating the member, and springs for returning the shaft to normal position with means for turning the stamping member in one direction as it is moved to operative position and means for turning the stamping member in the opposite direction as it is raised from operative position.

8. A hide splitting horse, a member connected to the horse; a shaft carrying said member and depending below the horse, a device carried by said member; a treadle pivotally supported on the horse; a connection between the treadle and the shaft for operating the latter, springs for returning the shaft and member to normal position, and means for turning the member in one direction as it is moved to operative position and for turning the member in the opposite direction as it is raised from operative position.

9. A hide splitting horse having parallel top bars; a pair of members mounted on the 125 horse adjacent one end of the bars; spring means for normally holding the said members in raised position, and means for simultaneously depressing the said members; with means for turning the members toward each 130

other as they move to operative position and for turning them away from each other as they move away from operative position.

10. A stamping mechanism comprising a longitudinally and rotatably movable shaft, a stamping member carried thereby, means for depressing the shaft so as to operate the stamp member, and means whereby the shaft is turned in one direction when the stamp is moved to impress the hide and turned in the opposite direction when the stamp is retracted.

11. A stamping mechanism comprising a stamping member, a longitudinally movable shaft carrying said member, means for reciprocating said shaft, and means whereby the shaft is turned in one direction when it is lowered to bring the stamp to operative position and is turned in the opposite direction when raised to turn the stamp away from operative position.

12. In combination stamping members, means for raising and lowering the stamping members, means for causing the stamping members to approach each other as they are lowered, and means for causing the stamping members to separate as they move from operative position.

13. In combination a pair of vertically movable shafts, stamping members carried by said shafts, means for raising and lowering the shafts, a pair of arms connected with said shaft, a spring connected with said arms to rock the shafts in one direction, other arms connected with said shafts, and means connected with the latter arms whereby the shafts are rocked in opposition to the spring, substantially as described.

14. In combination, a pair of vertically movable shafts, members carried by said shafts and devices carried by said members, a treadle and connection for reciprocating the shafts, and means whereby when the shafts are lowered they are caused to turn and swing the devices toward each other as they approach operative position, and whereby the shafts are turned so as to swing the said members away from each other as they are raised from operative position.

15. In mechanism of the character specified the combination of a horse, a pair of vertically movable shafts connected therewith, members carried by said shafts, means for raising and lowering the shafts, a pair of arms connected with said shaft, a spring connected with said arms to turn the shafts in one direction, other arms connected with said shafts and connections whereby the shafts are turned opposite to the spring, the shafts being turned so as to move the members toward each other as they are lowered to operative position, and the members being turned away from each other as they are raised from operative position.

16. In combination a vertically movable

shaft, a member on said shaft carrying a device, a treadle and connections for reciprocating the shaft, a spring connected with said shaft to turn it in one direction, an arm connected with the shaft and means connected with the latter arm whereby said arm is operated by the treadle when the latter rises, whereby when the shaft is lowered it is caused to swing the device toward operative position, and whereby the shaft is turned so as to swing the said device away from operative position as it is raised.

17. In combination a pair of vertically movable shafts, members carried by said shafts, devices carried by said members, means for reciprocating the shafts, arms connected with said shafts, a spring connected with said arms to cause the shafts to turn in one direction, other arms connected with the shaft and means engaging the latter arms; whereby when the shafts are lowered they are caused to rotate to swing the devices toward each other as they approach operative position, and are turned so as to swing the said devices away from each other as they are raised from operative position.

18. In combination a pair of vertically movable shafts, members carried by said shafts, devices carried by said members, a treadle and connections for reciprocating the shafts; arms connected with said shafts, a spring connected with said arms to cause the shafts to turn in one direction; other arms connected with the shafts, a rocking lever, links connecting said lever with the latter arms, said lever being operated by the treadle when the latter rises; whereby when the shafts are lowered they are caused to rotate to swing the devices toward each other as they approach operative position, and are turned so as to swing the said devices away from each other as they are raised from operative position.

19. A hide splitting horse; a member connected to the horse; a shaft carrying said member and depending below the horse; a device carried by said member; a treadle pivotally supported on the horse; a connection between the treadle and the shaft for operating the latter; and springs for returning the shaft and member to normal position; with means for turning the member in one direction as it is moved to operative position and means for turning the member in the opposite direction as it is raised from operative position.

20. A mechanism comprising a longitudinally and rotatably movable shaft, a member carried thereby, a cutter carried by said member, means for depressing the shaft so as to operate the member, and means whereby the shaft is turned in one direction when the member is moved to cause the cutter to incise the hide and turned in the opposite direction when the member is retracted.

21. A mechanism comprising a member carrying a cutter, a longitudinally movable shaft carrying said member, means for reciprocating said shaft, and means whereby the shaft is turned in one direction when it is lowered to bring the cutter to operative position and is turned in the opposite direction when raised to turn the cutter away from operative position.
- 5
22. In combination members carrying cut-

ters, means for raising and lowering the members, means for moving the members to cause the cutters to approach each other as they move to operative position, and means for causing the members to separate the cutters as they move from operative position.

In testimony that I claim the foregoing as my own, I affix my signature.

JEWETT FOWLER NEILEY.
